UNITED STATES PATENT OFFICE.

JAMES H. DAVIS, OF CHICAGO, ILLINOIS, ASSIGNOR TO THE AMERICAN STEAM HEATING SPECIALTY COMPANY, A CORPORATION OF NEW JERSEY.

AUTOMATIC CONTROLLING DEVICE FOR STEAM-HEATING SYSTEMS.

SPECIFICATION forming part of Letters Patent No. 716,850, dated December 23, 1902.

Application filed March 23, 1900. Serial No. 9,830. (No model.)

To all whom it may concern:

Be it known that I, JAMES H. DAVIS, of Chicago, county of Cook, and State of Illinois, have invented an Improvement in Automatic Controlling Devices for Steam-Heating Systems, of which the following is a specification.

My invention relates to automatic controlling devices for steam-heating systems; and it consists of the improvements which are fully set forth in the following specification and are shown in the accompanying drawings.

It is the object of my invention to enable the discharge-outlet of a radiator or other part of a steam heating apparatus to be controlled automatically to permit the water of condensation and air to escape without waste of uncoupled steam; and my invention is particularly adapted to that class of steam-heating systems in which the air and water of condensation are drawn out of the radiators, coils, or heaters by a partial vacuum or lower pressure created in the returns. In such systems without careful regulation or adjustment of the discharge from the radiators, &c., there is liability of an excess of steam being drawn through some lines with a deficiency through others, resulting not only in waste of steam, but also in defective circulation. Thermostatic valves are used in such systems to prevent the escape of steam by the expansion, under the action of steam, of an expandable outlet-controlling plug or tube; but it is the object of my invention to accomplish this result automatically without the use of such thermostatic expanding devices. This I have heretofore accomplished by the use of a float-controlled valve for the main outlet for water of condensation and an auxiliary small air-outlet independent of the control of the valve, which remains at all times open and through which the air is discharged when the main outlet is closed. In such devices, owing to the small area of the float exposed to the action of the small volume of water in the valve-body, the suction or lower pressure in the return tends to prevent the movement of the float and to hold the valve closed.

It is one of the objects of the present invention to enable a maximum area of the float to be subjected to the action of the wa-

ter of condensation in a valve-body of given size, so that the tendency of the suction to hold the valve closed may be overcome.

It is another object of my invention to insure the constant discharge of the air without interference by accumulations of water of condensation which might not be sufficient to open the float-controlled discharge-valve.

My invention also relates to other improvements in construction designed to make the valve device more certain and positive in its action.

In the drawings, Figure 1 is a diagrammatic view illustrating the application of my invention to a steam-heating system of the character referred to. Fig. 2 is a vertical sectional view of the valve device. Fig. 3 is a plan view of the same with the top cap or cover removed, and Fig. 4 is a detail view showing the controlling-valve and part of the float.

A is the valve-body, having an inlet a and an outlet b. The valve-body is preferably cup-shaped or recessed internally, as at C, 75 with the inlet a opening into the upper portion thereof and the outlet b leading from the bottom.

D is a tube extending from the outlet b upward in the body A and is provided with 80 one or more openings d near the base, which communicate with the outlet b and form therewith the main thoroughfare for the escape of the water of condensation. The upper end of the tube D is provided with a 85 small or constricted opening e for the escape of air.

E is the float within the body A, carrying a valve or gate c, which controls the main outlet d. As shown, the float E is provided 90 with a central tubular opening B, which fits upon the tube D, and the valve c is an extension or projection of the tube B, by which the central opening is formed. The tube D thus acts as a tubular guide for the float B 95 and forms an air passage-way between the outlet and the upper part of the valve-body.

F is the cap or cover of the valve-body.

G is a screen between the inlet a and the outlet d b. This screen is preferably cup-shaped, fitting within the cup-shaped portion C of the valve-body, and supported at a slight

elevation above the surface thereof by a flanged edge *g*, clamped between the top of the body *A* and cap *F*. The tube *D* projects through the screen *G*, which thus acts not only as a screen to prevent particles of solid matter passing into the valve-outlet but also as a support for the float *E*, which it sustains at a slight distance from the surface of the cup-shaped recess *C*.

10 As the outlet *d b* is situated at a substantial distance below the inlet *a*, the cup-shaped recess *C* will form a receptacle of sufficient size for the accumulation of a substantial volume of water, and as the float *E* extends 15 within this recess *C* to a substantial extent a sufficiently large area of the float may be subjected to a sufficient volume of water to obtain the necessary flotation to overcome the action of the suction without increasing 20 the size of the valve device to an objectionable extent.

In applying the valve device to a suction system the inlet *a* is coupled with the outlet of the radiator or coil *J*, to which the steam 25 is supplied from the exhaust *M* or from any other suitable source, and the outlet *b* is coupled with the return *K*, in which a partial 30 vacuum or lower pressure is created by the pump or exhausting device *L*. As the air-outlet *e* is constantly open, the air is constantly exhausted from the radiators, &c.; but owing to the small size of the opening *e* there is no appreciable waste of steam, such as would occur through an outlet, such as *b* 35 *d*, of sufficient size for the discharge of water. As the water of condensation accumulates in the body *A* it lifts the float and opens the valve; and the water is drawn out, the valve automatically closing when the water is 40 discharged.

The details of construction shown may be varied without departing from the invention.

What I claim as new, and desire to secure by Letters Patent, is as follows:

1. An automatic valve device for steam- 45 heating systems, consisting of a valve-body having an inlet and an outlet, an extended tube communicating with said outlet and having a passage-way for the escape of water of condensation into said outlet near its base 50 and a constricted opening for the escape of air at the top, and a float provided with a tubular passage-way loosely embracing said extended tube and carrying a gate or valve for normally closing the lower passage-way for the 55 escape of water through said tube, and a screen surrounding the lower portion of said float and acting as a support for said float and its valve when in lowered position.

2. An automatic valve device for steam- 60 heating systems, consisting of a valve-body having an internally cup-shaped or recessed base with an inlet and an outlet leading respectively from the upper and lower portions thereof, a valve to control said outlet, a float 65 controlling said valve and extending into said cup-shaped or recessed base, a perforated cup-shaped diaphragm or screen within said cup-shaped base supporting said float out of contact with the surface of said base, and said 70 valve device being provided with an air passage-way independent of the control of said valve for the escape of air while said valve is closed.

In testimony of which invention I have here- 75 unto set my hand.

JAMES H. DAVIS.
